[57] CLAIM

The ornamental design for a combined display unit and stand therefor, as shown and described.

DESCRIPTION

FIG. 1 is an isometric view of a combined display and stand therefor showing our new design;

FIG. 2 is a front elevational view thereof, with the support omitted for ease of illustration;

FIG. 3 is a side elevational view thereof, the opposite side being a mirror image of the side shown;

FIG. 4 is a bottom plan thereof;

FIG. 5 is a rear elevational view thereof;

FIG. 6 is a side elevational view thereof, the opposite side being a mirror image of the side shown;

FIG. 7 is a bottom plan view of the display unit shown in FIG. 5;

FIG. 8 is a side elevational view of a combined display unit and a stand shown in FIG. 1;

FIG. 9 is a side elevational view thereof in an alternative position;

FIG. 10 is a top plan view thereof the stand being in a vertical position; and,

FIG. 11 is a modified embodiment of a front elevational view of the display unit shown in FIG. 5.
